United States Patent Office

Des. 177,749
Patented May 22, 1956

177,749

SUPPORTING STAND FOR POTTED PLANTS OR THE LIKE

Earl J. Oliver, Castro Valley, Calif.

Application August 9, 1955, Serial No. 37,391

Term of patent 14 years

(Cl. D35—3)

Fig. 1.

Fig. 2.

I claim:

The ornamental design for a supporting stand for potted plants or the like, substantially as shown.
